DESIGN FOR A SCALE CASING

Alfred Bousfield, Brooklyn, N. Y.

Application March 9, 1935, Serial No. 55,794

Term of patent 7 years

To all whom it may concern:

Be it known that I, Alfred Bousfield, a citizen of the United States, residing at Brooklyn, in the county of Kings and State of New York, have invented a new, original, and ornamental Design for a Scale Casing, of which the following is a specification, reference being had to the accompanying drawing, forming part thereof.

I claim:

The ornamental design for a scale casing, as shown.

ALFRED BOUSFIELD.
